DETACHABLE HANDLE

Edward W. Stevens, Detroit, Mich., assignor to
Chicago Pneumatic Tool Company, New York,
N. Y., a corporation of New Jersey

Application July 21, 1931. Serial No. 552,187

15 Claims. (Cl. 121—36)

This invention relates to percussive power tools and more particularly to auxiliary handles therefor which can be conveniently attached and detached.

- 5 One object of the invention is to extend the usefulness and increase the adaptability of percussive tools of the hand supported type. Another object is to permit the application of greater force when the tool is in contact with the work. 10 Another object is to provide for convenient oscillation of the tool drilling operations. Still another object is to devise a detachable head of the cross head of T type adapted for light hand tools and usable with or without a push plate. 15 Other objects will be apparent from the detailed description which follows.

By the use of a detachable handle of the present invention in combination with a light weight percussive tool of the type commonly referred to as 20 coal picks, the utility of the tool is greatly increased. In coal mining, for example, the general practice of drilling and blasting can be at least partially modified to effect rather marked economies in operating costs as well as in equipment 25 and in maintenance of the latter.

As an example we will consider that a coal vein about three feet thick has an underlying stratum of slate also about three feet thick. By cutting to a total depth of six feet, sufficient head room 30 for men and mine cars will be provided. The drift may be cut to any desired width. Starting with a flush wall face, the coal pick hammer without the cross handle attachment is manually operated and by driving into the coal vein at an angle, 35 pieces of coal will be broken out rapidly. With one man to shovel the loose coal back into a waiting mine car a greater tonnage can be produced than by the former method of drilling and blasting, mainly because no time is lost waiting for 40 the drift to clear of smoke and gas caused by the explosions.

After the coal has been cut away to a substantial depth, as some twelve feet, it becomes necessary to remove the underlying stratum of slate 45 in order to bring the mine cars up to the working face. Drilling and blasting is the quickest method and for the drilling, the detachable cross handle and push plate of the present invention may be applied to the coal pick hammer. The peg 50 point steel is removed and a drill steel about twelve feet long is substituted. These changes convert the tool into a hand rotated rock drill which can be easily operated by one man. Thus 55 where two different types of machines were formerly used, one will now do the work so that

there is not only a saving in time but the capital investment is reduced at least 50%, without considering the economies in maintenance.

Additional uses for light percussive tools after application of the detachable handle are in hitch cutting, demolition work, tie tamping, clay spading, and the like. The push plate is normally used only in such cases as horizontal drilling where considerable pressure is required to feed the drill. Hence it is conveniently removable 60 from the handle attachment. The push plate is arranged to swivel freely at its point of attachment and may be applied against chest, thigh, or knees.

In order to illustrate the invention concrete 70 embodiments thereof are shown in the accompanying drawings, in which:

Fig. 1 is a side elevational view of a percussive tool with one form of the invention, the detachable handle and the cooperating part of the tool 75 being shown partly in section;

Fig. 2 is a top plan view of the parts shown in Fig. 1;

Fig. 3 is a view similar to Fig. 1 but showing a modified form of the invention, partly in section, 80 applied to the handle portion, also in section, of a different form of percussive tool;

Fig. 4 is a plan view of the handle shown in Fig. 3 with the push plate member removed; and

Fig. 5 is a side elevational view of the push 85 plate member for the handle shown in Figs. 3 and 4.

In Figs. 1 and 2, one form of detachable handle is disclosed as applied to a push-handle type of light weight percussive tool comprising a cylinder A, having a working tool B, such as a peg point or drill steel, inserted in its forward end and held in operative relation with a hammer piston (not shown) by a coil spring retainer C. The backhead member D of the drill has an 90 axially movable element E providing a handle with a hollow grip portion e. If pressure is applied to element E it moves forward on member D and actuates a throttle valve (not shown) for admitting motive fluid, such as compressed air, to 95 operate the hammer. Such a tool and its manner of operation is well known, the tool shown corresponding substantially to the disclosure of U. S. Patent No. 739,609, issued September 22, 1903 to H. G. Kotten.

The detachable handle adapted to be applied to the tool described above comprises a substantially straight member 6 providing hollow grip portions 7 and 8 and enlarged central portion 9 having socket 10 shaped to fit and to receive the 110

grip portion *e* of the percussive tool. Bore 11 of handle 6 lines up and registers with the bore in grip portion *e* when the detachable handle is applied to permit the insertion of a locking member, such as a pin 12, which is inserted through grip portion 7 through a bore of grip portion *e* of the hammer, and within grip portion of the detachable handle 8. The head 13 of pin 12 may have screw-threaded connection with bore 11 to secure the locking pin against accidental removal. Central portion 9 of handle 6 has an extension 14 in the form of a boss over which telescopes the sleeve portion 15 of a push plate 16. The push plate is arranged to swivel on boss 14 and is freely removable therefrom. A spring ring 17 in a groove in extension 14 may provide frictional resistance to its removal.

The modified form of detachable handle shown in Figs. 3, 4 and 5, is shown in Fig. 3 as applied to a somewhat different but common type of light percussive tool F provided with a manually controlled throttle valve G and having a hand control H on the hammer cylinder for closing the main exhaust port to blow cuttings out of a drill hole when a hollow drill steel is used as the working tool. The backhead I for hammer cylinder F carries throttle valve G and provides a throttle lever J having its handle end disposed adjacent hollow-grip portion *i* which forms a part of backhead I, so that when the grip portion is grasped by the operator throttle lever J can be conveniently manipulated. Grip portion *i* has a slot *i*² intersecting the bore thereof and in line with throttle lever J for a purpose presently to be described. Detachable handle 6^a conforms in major respects to the form shown in Figs. 1 and 2 in that it has end grips 7^a and 8^a, a large central portion 9^a providing a socket 10^a shaped to fit and receive grip portion *i* of backhead I, an extension or boss 14^a and a push plate 16^a removably mounted on boss 14^a. In this instance push plate 16^a has a stud 15^a having a projecting portion which telescopes within a bore in boss 14^a. The effect is that the push plate 16^a will swivel upon handle 6^a in substantially the same manner as push plate 16 on handle 6 of the first form of the invention.

Different means are used to secure handle 6^a in place as compared with the first form of the invention through the necessity of some means on the detachable handle for operating throttle lever J. The locking means comprise plungers 18 mounted in grip portions 7^a and 8^a and having their ends projectable into socket 10^a to engage the bore of handle portion *i*. Plungers 18 are yieldingly retained in extended or locking position by coil springs 19 encircling reduced portions of the plungers and mounted in counterbored portions of handle bore 11^a. Plungers 18 have bearings in perforated plugs 20 and buttons 21 on their outer ends by which they may be retracted when handle 6^a is to be applied or to be removed. In order to actuate throttle lever J, a lever 22 is pivotally mounted upon central section 9^a with its actuating end 22^a extending through registering slots 23 and *i*² to engage lever J and with its handle portion 22^b adjacent grip portion A for convenient operation by the hand which grips the end 8^a.

From the above the manner of mounting and removing detachable handle 6 or 6^a will be obvious. When either handle is in place, light percussive tools such as A and F are readily adapted to drilling and sinking operations inasmuch as ample leverage is given by aligned grip portions

7, 8 and 7^a, 8^a for oscillating the entire tool, and consequently the drill steel, to prevent sticking of the latter. With a push handle tool, such as A, control of the motive fluid is effected by pressure on handle 6. When the invention is applied to a tool, such as F, with an inside throttle lever, operation of the latter is effected by an actuating lever, such as 22, on handle 6^a. If heavy pressure is required to feed the drill steel, push plate 16 or 16^a is applied to the detachable handle for application against some part of the operator's body. Since the push plate swivels freely on the detachable handle, the push plate does not interfere with oscillation of the T handle to speed up the drilling.

I claim as my invention:

1. The combination with a light weight percussive tool having a back head and an extension thereon having a bore transverse to the axis of said tool, of a detachable handle member having a socket receiving said extension and means engaging said bore to secure said member in place.

2. The combination with a light weight percussive tool having a back head and an extension thereon having a bore transverse to the axis of said tool, of a detachable handle member having a socket receiving said extension, and means engaging said bore from opposite ends thereof to secure said member in place.

3. The combination with a light weight percussive tool having a back head and an extension thereon having a bore transverse to the axis of said tool, of a detachable handle member having a socket receiving said extension, and a bore registering with said back head bore, and a locking pin extending into both bores to secure said member in place.

4. The combination with a light weight percussive tool having a back head and an extension thereon having a bore transverse to the axis of said tool, of a detachable handle member having a socket receiving said extension, and a bore registering with said back head bore, a locking pin extending into both bores to secure said member in place, and means securing said pin to said member.

5. The combination with a light weight percussive tool having a back head and an extension thereon having a bore transverse to the axis of said tool, of a detachable handle member having a socket receiving said extension, and a bore registering with said back head bore, and means in said bore of said member for engaging said back head bore to secure said member to said tool.

6. The combination with a light weight percussive tool having a back head and an extension thereon having a bore transverse to the axis of said tool, of a detachable handle member having a socket receiving said extension, and a bore registering with said back head bore, and means in said bore of said member engaging said back head bore from opposite ends to secure said member to said tool.

7. The combination with a light weight percussive tool having a back head and an extension thereon having a bore transverse to the axis of said tool, of a detachable handle member having a socket receiving said extension, and a bore registering with said back head bore, and spring pressed plungers in said bore of said member extending into said socket to engage said back head bore from both sides securely to lock said member to said tool.

8. The combination with a light weight percussive tool having a back head and an extension

- thereon having a bore transverse to the axis of said tool, of a detachable handle member having a socket receiving said extension, and a push plate mounted for swivelling movement on said member above said socket and detachable therefrom.

9. The combination with a light weight percussive tool having a back head and an extension thereon having a bore transverse to the axis of said tool, of a detachable handle member having a socket receiving said extension, said member having a boss above said socket, and a push plate detachably mounted for swivelling movement on said boss.

10 15 20 25 30 35 40 45 50 55 60 65 70 75 80 85 90 95 100 105 110 115 120 125 130 135 140 145 150

10. In combination, a light percussive power tool having a grip handle with an end recess therein, and a detachable T handle comprising a substantially straight member having grip portions at its ends and a central portion provided with a socket to fit over and receive the grip handle of the tool, and means to engage the recess in the grip handle to secure the detachable handle to the latter.

11. In combination, a light percussive power tool having a grip handle with an end recess therein, and a detachable T handle comprising a substantially straight member having an axial bore, grip portions at its ends and a central portion formed with a socket to fit over and receive the grip handle of the tool, and means within said axial bore projectable into said socket for engagement with the recess in said grip handle to secure the detachable handle to the latter.

12. In combination, a light percussive power tool having a grip handle with an end recess therein, and a detachable T handle comprising a substantially straight member having hollow grip portions at its ends and a central portion formed with a socket to fit over and receive the grip handle of the tool, and retractable spring-pressed plungers within said grip portions extending into said socket to engage the recess in said grip handle to secure the detachable handle to the latter.

13. In combination, a light percussive power tool having a grip handle with an end recess therein, and a detachable T handle comprising a substantially straight member having hollow grip portions at its ends and a central portion formed with a socket to fit over and receive the grip handle of the tool, and retractable spring-pressed plungers within said grip portions extending into said socket to engage the recess in said grip handle to secure the detachable handle to the latter, and means mounting a detachable push plate for swivelling movement upon said central portion.

14. In combination, a light percussive power tool having a grip handle with an end recess therein, and a detachable T handle comprising a substantially straight member having hollow grip portions at its ends and a central portion formed with a socket to fit over and receive the grip handle of the tool, and retractable spring-pressed plungers within said grip portions extending into said socket to engage the recess in said grip handle to secure the detachable handle to the latter, and means mounting a detachable push plate for swivelling movement upon said central portion.

15. In combination, a light percussive power tool having a grip handle with an end recess therein, and a detachable T handle comprising a substantially straight member having hollow grip portions at its ends and a central portion formed with a socket to fit over and receive the grip handle of the tool, and retractable spring-pressed plungers within said grip portions extending into said socket to engage the recess in said grip handle to secure the detachable handle to the latter, said central portion having a slot therethrough, an actuating lever pivoted to said central portion and extending through said slot and transversely of said socket, the handle of said lever extending over one of said grip portions, a boss on said central portion, and a push plate having a stud for telescoping engagement with said boss for mounting said plate on said handle for swivelling movement.
